US0D1073458S

(12) **United States Design Patent** (10) **Patent No.:** **US D1,073,458 S**
(45) **Date of Patent:** **** May 6, 2025**

(54) **BALUSTER CONNECTOR**

(71) Applicant: **Yuejiao Su**, Changzhou (CN)

(72) Inventor: **Yuejiao Su**, Changzhou (CN)

(**) Term: **15 Years**

(21) Appl. No.: **29/973,477**

(22) Filed: **Nov. 15, 2024**

(51) LOC (15) Cl. **08-08**

(52) U.S. Cl.

USPC **D8/382**; D25/133

(58) **Field of Classification Search**

(57) **CLAIM**

The ornamental design for a baluster connector, as shown and described.

DESCRIPTION

FIG. 1 is a front perspective view of a baluster connector, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the baluster connector, which form no part of the claimed design.

1 Claim, 8 Drawing Sheets
